UNITED STATES PATENT OFFICE.

JOHN F. STREIB, OF AVALON, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

Application filed September 5, 1923. Serial No. 660,984.

An object of the present invention is to provide a railway freight car which will have the maximum width within the clearance limits allowed, so as to obtain a maximum capacity and yet permit of the application of the coping members, side sills, side braces or stakes, etc. without increasing the over all dimensions of the car.

Another object of the invention is to provide a freight car wall construction which will permit of the heaping of a greater amount of lading on the car than has heretofore been possible.

A further object of the invention is to provide a novel post or brace construction for a railway freight car in which a portion of such brace or stake is arranged inside of the car and a portion outside of the car, and all within the outside vertical plane of the side wall.

A still further object of the invention is to provide a novel coping construction for a railway freight car.

These and other objects will be apparent from the following description:

Referring now to the drawings in which like reference characters refer to like parts, Fig. 1 is a side elevational view of a portion of a car embodying the invention; Fig. 2 is an enlarged end elevational view of the same; Fig. 3 is an enlarged cross sectional view of the same, taken on the line 3—3 of Fig. 1 and Fig. 4 is an enlarged plan view of one of the corner portions of the car.

Referring now in detail to the drawings, the reference character 1 indicates the car body which preferably comprises side walls 2, side sills 3, sloping side floors 4, sloping end floors 5 and discharge doors 6.

Each of the side walls 2 comprises a plate 7 having a vertically disposed portion 8 and an inwardly and upwardly sloping top portion 9. To stiffen and strengthen the side wall a coping member 10 is provided which is of angular form having a flange 11 secured to the portion 9 of the side wall and also having a flange 12 forming an upward extension of the side wall. This member is so positioned that the flange 11 will slope inwardly and upwardly at substantially the same angle as the portion 9 of the side wall while the flange 12 will slope upwardly and outwardly from the flange 11 and this coping member as a whole will be within the

outside vertical plane of the portion 8 of 55 the side wall.

Each of the sloping side floors preferably comprises a plate having a vertically disposed upper portion 13 which is secured to the lower portion of the plate 7, an inwardly and downwardly sloping portion 14 and a vertically disposed lower portion 15 which portion 15 defines one of the sides of the discharge opening, such opening being 60 65 closed by the doors 6.

The side sills are preferably of channel form having their webs 16 disposed vertically and their flanges 17 disposed horizontally and directed inwardly toward the longitudinal center line of the car. Each 70 of these side sills is located beneath the sloping portion 14 of one of the side floors and inside of the outside vertical plane of the portion 8 of the side wall. To connect the side sill and sloping side floor 4, a plate 18 is provided which is disposed horizontally and at one side is secured to the upper flange of the sill and at the opposite side 75 is bent downwardly to form a flange 19 which is secured to the lower portion 15 of the sloping side floor and further transverse members 20 are provided which are secured to the sill, plate 18 and vertical portion 15 of the sloping side floor. At each side of the car and on each side of the transverse 80 center line thereof a brace member 21 is provided which has a vertically disposed web 22, a bottom flange 23 which is secured to the upper flange of the side sill and plate 18 and also has a side flange 24 which is secured to the sloping portion of the side floor. The web 22 of this member extends outwardly 85 beyond the outside vertical plane of the web of the side sill and is connected with an outwardly extending flange 25 of a vertically disposed angular member 26, the flange 27 of such member being secured to the web of the side sill and to the sloping portion 14 of the side floor. It will be noted that the construction just described is located wholly 90 within the outside vertical plane of the portion 8 of the side wall.

Within the body of the car and on each side of the transverse center line thereof, a stake 28 is provided which is preferably of flanged U shape and comprises a raised portion or corrugation 29 and flanges 30 which flanges and corrugation extend for substan-

tially the full length of the stake. The upper portion 31 of the stake is disposed vertically and the flanges 30 of this part of the stake are for the greater portion of their 5 length, secured to the portion 8 of the side wall. These flanges adjacent their upper ends are directed inwardly and upwardly as indicated by the reference character 32 and are secured to the flange 11 of the coping 10 member 10. The lower portion 33 of this stake is directed downwardly and inwardly at an angle to the upper portion 31 and the flanges 30 of this lower portion of the stake are secured to the sloping portion 15 14 of the side floor. This portion 33 of the stake extends downwardly and inwardly on the sloping floor and overlies the brace member 21, one of the flanges 30 being connected with the sloping side floor and the other 20 25 of these flanges being connected with the sloping side floor and brace member 21. It will here be noted that the brace member 21 and angular member 26 are located outside of the car body and the stake 28 is located inside of the car body and these members are so disposed and connected together that they form in effect a continuous stake from the coping member 10 to the side sill 3. Between the flanges 11 and 12 of the coping member 30 35 10 a brace member 34 is provided having flanges 35 and 36 which are secured to the flanges 11 and 12 respectively, the flange 35 also being secured to the portion 32 of the flanges 30 of the stake 28. This member 34 is preferably provided with a rib or corrugation 37 which extends vertically between the flanges 35 and 36. This member 34 serves to stiffen the flanges of the coping member 10 and forms in effect an upward 40 extension of the stake 28.

Adjacent each end of each side wall, a vertically disposed stake 38 is provided, which is preferably of flanged U shape, having a rib or corrugation 39 and flanges 40. The lower portions of the flanges 40 are secured to the web 16 of the side sill while the side wall 2 overlaps the upper portion of the stake and is secured to the rib or corrugation 39.

Between each of the stakes 28 and 38 and within the body of the car, the side wall is provided with a vertically disposed stiffening member 40^a which is preferably of flanged U shape having a rib or corrugation 41 and flanges 42 which flanges are secured to the portion 8 of the side wall. Adjacent the top of the member these flanges are bent inwardly and upwardly and are secured to the flange 11 of the coping member. On the 45 outside of the car body and extending between and secured to the flanges 11 and 12 of the coping member and to the flanges 42 adjacent the top of the member are brace members 34 which have been hereinbefore 50 described in connection with the stake 28.

As illustrated in the drawings the member 40^a extends a short distance below the coping member 10 but it will be understood that in some cases these members may be made longer or may be made substantially the 55 same as the stake 28.

Beyond each of the stakes 38 and at each side of the car a vertically disposed stake 43 is provided which is preferably of angular form having flanges 44 and 45. The 60 flange 44 is disposed in a direction towards the transverse center line of the car and at its lower end is secured to the web 16 of the side sill while the flange 45 is disposed in a direction toward the longitudinal center line of the car and at its lower end is connected with downwardly depending flange 46 of a platform plate 47 through the medium of a plate 48 which is secured to the flange 45 of the stake and the flange 46 of the platform plate. The upper portion of this stake is connected with the upper portion of the stake 38 through the medium of a plate 49 which at one end is secured to the flange 44 of the stake 43 and at its opposite end to one of the flanges 40 of the stake 38. The upper portion of this plate is provided with an outwardly extending horizontal flange 50 which is secured to a cap or gusset member 51 hereinafter more fully described.

Each of the end floors 5 slope downwardly and inwardly toward the transverse center line of the car. This floor may be of any preferred form or construction and is preferably provided with upwardly extending side portions 52 which are secured to the side walls and sloping floor. This floor adjacent its top edge is provided with a coping member 53 having a flange 54 which is secured to the outside of the floor and also 105 having an outwardly projecting flange 55.

Each of the cap or gusset members 51 hereinbefore described is provided with a horizontally disposed top portion 56 which is secured to the flange 50 of the plate 49 and is also provided with an end portion 57 which slopes downwardly and inwardly and is secured to the flange 12 of the coping member 10. The portion 57 extends some distance below the flange 12 and is connected with the flange 11 of the coping member through the medium of an angular member 58, one flange of which is secured to the flange 11 of the coping member and the other flange is secured to the portion 57 of the member 51. The opposite end portion of this member 51 is provided with a downwardly extending flange 59 which is secured to the flange 45 of the stake 43. The side portion 60 of the member 51 is 115 preferably sloped downwardly and inwardly and at 61 contacts with and is secured to the sloping end floor. It will be noted that this member 51 ties the top portions of the side wall and sloping end floor firmly to 120

gether and also serves to connect the posts 38 and 43 and plate 49 together, thus forming a very strong and rigid corner construction for the car body.

5 The plate 49 intermediate the stakes 38 and 43 is offset inwardly and is secured to the sloping end floor thus further connecting the end floor and side wall.

Each of the side ladders is formed by extending ladder rungs 62 between the stakes 38 and 43 and securing one end of each rung to one of the flanges 40 of the stake 38 and the opposite end to the flange 44 of the stake 43. These flanges 40 and 44 are located some distance inside of the outside vertical plane of the side wall and when the rungs 62 are secured thereto as just described the ladder as a whole will be within the outside vertical plane of the side wall.

10 From the foregoing description it will be seen that there are no parts of the car body which project beyond the outside vertical plane of the side wall and thus a car body is provided having a maximum width within 25 clearance limits allowed.

Having thus described the invention, what I claim as new and desire to secure by Letters Patent is:—

1. In a freight car, a wall having a vertically disposed upper portion and an inwardly extending lower portion, a side sill, a brace between the lower portion of said wall and said sill and secured thereto and adapted to fill the space therebetween, a 35 stake on the inside of said wall, and a stake

arranged on the outside of said wall and secured to said sill brace and first mentioned stake.

2. In a freight car, a wall having an inwardly extending portion, a triangular 40 brace secured to said portion, said brace having a vertically disposed web, a side sill below said portion, and a vertically disposed member secured to said sill, vertically disposed web and portion. 45

3. In a freight car, a side wall having a vertically disposed upper portion and an inwardly sloping portion, a brace arranged beneath and secured to said lower portion, a side sill and a vertically disposed member secured to said sill, brace and portion, said brace and member being wholly within the vertical plane of the upper portion of said wall. 50

4. In a railway freight car, a side sill, a 55 side floor, a brace member secured to said sill and floor, said member having a web extending outwardly beyond said sill, and a member secured to said sill, floor and outwardly extending portion of said web. 60

5. In a railway freight car, a side floor, a brace member extending between and secured to said sill and floor, said members comprising a web projecting outwardly beyond said sill, and a vertically disposed 65 member secured to said sill and projecting portion of said web.

In testimony whereof, I affix my signature.

JOHN F. STREIB.
